UNITED STATES PATENT OFFICE.

ROBERT A. WURZBURG, OF PORTLAND, OREGON.

DESIGN FOR A TIRE.

Application filed March 1, 1924. Serial No. 8,800. Term of patent 14 years.

To all whom it may concern:

Be it known that I, ROBERT A. WURZBURG, a citizen of the United States, residing at Portland, in the county of Multnomah and State of Oregon, have invented a new, original, and ornamental Design for Tires, of which the following is a specification, reference being had to the accompanying drawing, forming a part thereof.

Figure 1 is a plan view of a portion of a tire, showing my new design, and,

Figure 2 is a transverse, sectional view of the tread portion thereof taken as indicated by the lines 2—2 of Figure 1 and indicating by dotted lines a portion of the tire body.

I claim:

The ornamental design for a tire as shown.
ROBERT A. WURZBURG.
